United States Patent Office

Des. 197,118
Patented Dec. 17, 1963

197,118

BUILDING

Manuel C. Avancena, 737 3rd St. SW., Washington, D.C., and Everett D. Vernaccini, Box 42, Rte. 1, Brandywine, Md.

Filed July 31, 1962, Ser. No. 71,123

Term of patent 14 years

(Cl. D13—1)

FIG. 1

Des. 197,118

PAGE 2

FIG. 2

FIG. 3

FIGURE 1 is a top plan view of a building showing our new design;

We claim:

The ornamental design for a building, substantially as shown.
